(57) **CLAIM**

The ornamental design for a building block shaped watch display box, as shown and described.

DESCRIPTION

FIG. 1 is a front perspective view of building block shaped watch display box showing my new design.

FIG. 2 is a front view thereof.

FIG. 3 is a rear view thereof.

FIG. 4 is a left end view thereof.

FIG. 5 is a right end view thereof.

FIG. 6 is a top view thereof.

FIG. 7 is a bottom view thereof.

FIG. 8 is a front perspective view thereof.

FIG. 9 is a rear perspective view thereof; and,

FIG. 10 is a rear perspective view thereof.

The broken line portion of the figure drawings is included to show unclaimed subject matter only and forms no part of the claimed design.
